UNITED STATES PATENT OFFICE

BENJAMIN F. MIESSNER, OF SHORT HILLS, NEW JERSEY, ASSIGNOR, BY MESNE ASSIGNMENTS, TO RADIO CORPORATION OF AMERICA, OF NEW YORK, N. Y., A CORPORATION OF DELAWARE

UNIDIRECTIONAL CURRENT SYSTEM

Application filed May 3, 1929. Serial No. 360,043.

The present invention relates to electrical unidirectional current supply systems, and particularly systems for supplying substantially non-fluctuating unidirectional current from sources of pulsating unidirectional current.

A particular object is the provision of means for substantially smoothing out or filtering the strongly pulsating unidirectional current resulting from rectifying alternating current as, for example, the practice of energizing the electrodes of vacuum tubes in signal current amplifiers from a commercial 25 or 60-cycle alternating current supply system without objectionable degree of hum.

A feature of my invention is the employment of thermionic or equivalent devices as an aid in filtering the pulsations from the unidirectional currents under treatment.

Further objects are apparent from the following description of the figures comprising the accompanying drawings in which like reference characters indicate corresponding parts throughout the several views, and in

Fig. 1 is a diagrammatic circuit arrangement of one form of my invention, and

Fig. 2 is a modification thereof.

Referring to the drawings, P_1 designates the primary of a transformer T_1 connected to a source A. C. of alternating current.

The transformer T_1 is provided with a plurality of low-potential three terminal secondaries S_1 and S_2 designed for filament heating. The secondary S_1 supplies filament heating current to a tube VT , the characteristics of which will be described in detail hereinafter.

The transformer T_1 is also provided with a three terminal high potential secondary S_3 , the outer terminals of which are connected to the anodes of a full wave rectifying tube RT , the filament of which is supplied with heating current from secondary S_2 . The mid-point of the secondary S_2 is connected to one terminal of a load W or system of work circuits through a variable choke coil L by means of leads 1 and 2. The work circuits may comprise for example the plate circuits of a cascade system of amplifier tubes.

The mid-points of the secondaries S_1 , S_3 , being connected together by a lead 5, are connected to the terminal of the load W by means of leads 3 and 4. The leads 1 and 3 serve as the terminals of a filter and storage condenser C_1 . The load W is preferably shunted by a storage and by-pass condenser C_2 .

In Fig. 1 VT is for example a high vacuum tube having a filament F and an anode A which is connected to the lead 2. The filament F is preferably a high temperature emissive filament of low heat inertia so that with potential changes occurring in the secondary S_1 the temperature of the filament F and the electronic emission thereof vary, which varying emission causes the impedance of the tube VT to change. These changes in the impedance of the tube are so phased with relation to the fluctuating component of the current flowing in the lead 2 that any variation in the potential of the lead 2 is compensated by an increase or a decrease in flow of current through tube VT .

In Fig. 2, VT' constitutes a three element vacuum tube which may be of the type above described or of the type shown and described in my copending application Serial No. 191,195, filed 13 May 1927, (Patent 1,718,059, June 18, 1929), and having a filament F , a grid G and an anode A which latter is connected to the lead 2. The lead 2 also includes the primary P_2 of a transformer T_2 , the secondary S_4 of which is connected between the grid G and the supply source end of a variable resistance R included in the lead 4. The mid-point of the secondary S_1 in this case is connected to the output end of the resistance R . By these connections the grid and filament of the tube VT' are maintained at a desired potential relative to each other for controlling the current flow through tube VT' .

Likewise the system shown in Fig. 2 operates to produce a ripple-free and hum-free source of potential at the terminals of load W . A variation in potential across the terminals of the primary P_2 acts through secondary S_4 onto grid G to vary the impedance of the tube VT' , so that the space current in

creases or decreases, thus varying the load between the leads 2 and 4. The transformer T_2 is so poled that these variations off-set those from the source. If a tube is used in Fig. 2 having the filament characteristics of the tube specified for Fig. 1, the action described in connection with Fig. 1 may be combined with the grid action to more effectively complete the filtration.

Having thus described two specific forms 10 of my invention in which an auxiliary load across the output terminals of a full-wave rectifier is varied in definite and phased manner to neutralize or off-set any ripple or hum 15 potential which normally would exist in the output of such a rectifier, and understanding that minor changes may be made therein but within the scope of my invention, what I claim is:—

1. In an electrical current supply system 20 the combination of a source of fluctuating current, a work circuit supplied therefrom and means for protecting said work circuit from the fluctuating component of said source, said means consisting of a three element tube, the plate-filament circuit of which is in shunt to said work circuit, a transformer, the primary of which is series connected between the plate of said tube and said 25 source, one terminal of the secondary of said transformer being connected to the grid of said tube and the other terminal of said secondary being connected to the filament of said tube.

2. In an electrical current supply system 30 the combination of a source of fluctuating current, a work circuit supplied therefrom and means for protecting said work circuit from the fluctuating component of said 35 source, said means consisting of a three element tube, the plate-filament circuit of which is in shunt to said work circuit, a resistance connected between the filament of said tube and said source, a transformer, the primary 40 of which is series connected between the plate of said tube and said source, one terminal of the secondary of which is connected to the grid of said tube and the other terminal thereof to a point in said resistance.

3. In an electrical current supply system 45 the combination of a source of fluctuating unidirectional current, a load to be supplied from said source, circuit connections between said source and said load, an impedance 50 bridged across said circuit connections, and means for automatically so varying the value of said impedance in consonance with the fluctuating current component of said source as to produce a permanent, fluctuating current drain therethrough of sufficient magnitude to offset said fluctuating component by reaction on said source.

4. In an electrical current supply system 55 the combination of a source of fluctuating unidirectional current, a load to be supplied

from said source, circuit connections between said source and said load, an impedance bridged across said circuit connections, said impedance including a thermionic tube with filamentary cathode of low thermal inertia, 70 and means for automatically so varying the value of said impedance in consonance with the fluctuating current component of said source as to produce a permanent, fluctuating current drain therethrough of sufficient magnitude to offset said fluctuating component by reaction on said source, said means including a source of varying potential connected to said filamentary cathode for cyclically energizing the same in consonance with the fluctuations of said source of unidirectional current whereby said impedance is varied in inverse relation to the fluctuating current component of said unidirectional source.

5. The combination with an electrical current supply system of a source of unidirectional current having a fluctuating component, a load connected to said source for energy supply therefrom, and means for protecting said load from the fluctuating component of said source, said means comprising a thermionic discharge tube having an anode and cathode connected in shunt to said load, said cathode being of low enough thermal inertia to permit temperature variations therein of the frequency of said fluctuating component and being energized from a cyclically varying source of potential of such frequency and in such phase relation to the fluctuating component of said source of unidirectional current as to change the impedance of said tube between finite values in inverse order to the potential variations of said unidirectional source.

6. In an electric-current supply system the combination of a source of uni-directional current having a fluctuating component, a work circuit connected to said source for energy supply therefrom, and means for protecting said work circuit from the fluctuating component of said source, said means including a three-electrode thermionic tube the anode-cathode circuit of which is in shunt to said work circuit, a transformer primarily energized from said source of unidirectional current and secondarily connected for unidirectional fluctuating energization of the control electrode of said tube in such phase relation to the fluctuating component of said source as to change the impedance of said anode-cathode circuit between finite values in inverse order to the potential variations of said source.

7. In an electric current supply system 125 the combination of a source of fluctuating unidirectional current, a work circuit connected to said source for energy supply therefrom, and means for protecting said work circuit from the fluctuating component of

said source, which means comprise a three-electrode thermionic tube the anode-cathode circuit of which is in shunt to said work circuit, a transformer primarily energized from said source of unidirectional current and secondarily connected for unidirectional fluctuating energization of the control electrode of said tube, and a cyclically varying source of potential connected to the cathode of said tube for energizing the same, which cathode has a low enough thermal inertia to permit temperature variations therein of the frequency of said fluctuating component, said energization of the control electrode from said transformer secondary and said energization of the cathode from said varying source of potential being both in consonance with and in such phase relation to the fluctuating component of said unidirectional source as to change the impedance of said anode-cathode current between finite values in inverse order to the potential variations of said unidirectional source.

8. In an electric current supply system the combination of a source of unidirectional current having a fluctuating component, a work circuit connected to said source for energy supply therefrom, a multiple-electrode vacuum tube having an anode, a cathode, and a control electrode and having its anode-cathode circuit connected across said work circuit, means for energizing said control electrode with a unidirectional fluctuating potential from said unidirectional current source with the aid of an inductive coupling therewith, and means for cyclically energizing said cathode, which cathode is of low thermal inertia, said energizations of the control electrode and the cathode being both predeterminedly proportioned and phased to coact in producing a resultant change of impedance in said tube of such magnitude and such phase relation with respect to said fluctuating current component that said work circuit will be protected from the fluctuating component of said unidirectional source.

In witness whereof, I have hereunto subscribed my name this first day of May, 1929.

50 BENJAMIN F. MIESSNER.
